UNITED STATES PATENT OFFICE.

ASHBEL P. BARLOW, OF ST. JOSEPH, MICHIGAN, ASSIGNOR TO PETER G. KNIEBES, OF BENTON HARBOR, MICHIGAN.

TRUSS.

No. 823,500.

Specification of Letters Patent.

Patented June 19, 1906.

Application filed June 1, 1905. Serial No. 263,359.

To all whom it may concern:

Be it known that I, ASHBEL P. BARLOW, a citizen of the United States, residing at St. Joseph, county of Berrien, State of Michigan, have invented a new and useful Improvement in Trusses; and I do declare the following to be a full, clear, and exact description of the invention, such as will enable others skilled in the art to which it appertains to make and use the same.

The object of this invention is to provide a truss for the treatment of hernia or rupture which is simple in construction, easily applied, and capable of adjustment to suit various conditions.

In the accompanying drawings, illustrating my invention, Figure 1 is an elevation showing the back of the truss. Fig. 2 is a similar view showing the front of the truss. Fig. 3 is a horizontal central sectional view.

Referring to the drawings, 5 represents two truss-pads which are connected and supported by a bowed plate 6, of spring metal. This plate is provided at its ends with a series of holes 7 to receive a threaded bolt 8, which is screwed in the pad and projects outward angularly from the back of the pad. The plate is secured on the bolt by a screw-nut 9, which in turn is held in place by a lock-nut 10. The series of holes in the plate enable the adjustment of the pad longitudinally of the plate, so that the pads can be arranged in proper position to meet the requirements of the wearer.

An adjusting-screw 11 projects through an opening in the plate located between the center of the plate and the bolt 8, and this screw is arranged at an angle to the pad and bears upon the back thereof. The nut 12 is arranged on the screw 11 between the plate and the pad to bear against the plate for holding the screw in position, and it may be adjusted to maintain the pad in any angular position that may be found desirable. Each of the pads is provided with adjusting devices of the kind heretofore described.

The truss is provided with hooks 13, buckles 14, and rings 15, to which are attached

the straps for securing the truss on the wearer.

The pad 5 comprises a bulb 16, which is held by the screw-bolt 8 on the disk 17 and inclosed within a bead 18. This bulb may be made either plain, as shown in the truss-pad at the right of Fig. 2, or transversely corrugated, as shown at the left of Fig. 2, the advantage of the corrugated bulb being that the corrugations will more effectually hold the intestines in place.

Having thus fully described my invention, what I claim, and desire to secure by Letters Patent, is—

1. A truss comprising a bowed spring-plate provided at each end with a series of openings disposed longitudinally of the plate, a truss-pad carried by the plate at its ends, said pad comprising a disk, a bulb, a bead on the disk surrounding the bulb, a screw-bolt screwed through the back of the disk and into the bulb, said screw-bolt being arranged in one of the openings in the plate, and a nut and a lock-nut on the bolt to fasten the pad, the bolt and the plate together.

2. A truss comprising a bowed spring-plate provided at each end with a series of openings disposed longitudinally of the plate, a truss-pad carried by the plate at its ends, and comprising a disk and a bulb, a screw-bolt passing through the disk and screwed into the bulb, said bolt being arranged in one of the openings in the plate, a nut and a lock-nut on the bolt to fasten the pad, the bolt and the plate together, an adjusting-screw passing angularly through an opening in the plate at one side of said screw and bearing upon the back of said disk, and a nut arranged on said bolt between the bulb and the plate, substantially as described.

In testimony whereof I have hereunto set my hand in the presence of two subscribing witnesses.

ASHBEL P. BARLOW.
